CLAIM

The ornamental design for a combination lock face, as shown and described.

DESCRIPTION

FIG. 1 is a perspective view of a combination lock face, showing my new design;

FIG. 2 is a front elevational view, thereof;

FIG. 3 is a side elevational view, the opposite side elevational view being a mirror image, thereof.

FIG. 4 is a top plan view, thereof; and,

FIG. 5 is a bottom plan view, thereof.

The broken-line representations of the lock body and closure member in the drawings are included solely for illustrative purposes, forming no part of the claimed design.
